(57) **CLAIM**

The ornamental design for a module body as shown and described.

DESCRIPTION

FIG. 1 is a first isometric view of a module body; FIG. 2 is a second isometric view of the module body; FIG. 3 is a third isometric view of the module body; FIG. 4 is a fourth isometric view of the module body; FIG. 5 is a first side view of the module body; FIG. 6 is a second side view of the module body; FIG. 7 is a front elevational view of the module body; FIG. 8 is a rear elevational view of the module body; FIG. 9 is a top plan view of the module body; and, FIG. 10 is a bottom plan view of the module body. The broken lines in the Figures show portions of a module body that form no part of the claimed design.
